[57] CLAIM

The ornamental design for a meter for analysis of blood constituents, as shown and described.

DESCRIPTION

FIG. 1 is a perspective view of a meter for analysis of blood constituents, showing our design;

FIG. 2 is a front elevational view of the meter for analysis of blood constituents of FIG. 1;

FIG. 3 is a back elevational view of the meter for analysis of blood constituents of FIG. 1;

FIG. 4 is a top plan view of the meter for analysis of blood constituents of FIG. 1;

FIG. 5 is a right side elevational view of the meter for analysis of blood constituents of FIG. 1;

FIG. 6 is a left side elevational view of the meter for analysis of blood constituents of FIG. 1; and,

FIG. 7 is a bottom plan view of the meter for analysis of blood constituents of FIG. 1.
